UNITED STATES PATENT OFFICE.

WILLIAM WINKLER AND ARTHUR H. MILLER, OF BROOKLYN, NEW YORK.

CASTER.

Application filed October 24, 1922. Serial No. 596,678.

To all whom it may concern:

Be it known that we, WILLIAM WINKLER and ARTHUR H. MILLER, citizens of the United States, and residents of Brooklyn, 5 in the county of Kings and State of New York, have invented certain new and useful Improvements in Casters, of which the following is a specification.

This invention relates to casters used with 10 articles of furniture and the main object is to provide an efficient and easily mounted caster which will readily facilitate the moving of such articles.

Another object is to provide a swivel type 15 of caster which consists of a minimum number of parts, any of which are easily removable, and is comparatively inexpensive in cost of manufacture.

These and other objects will become apparent in the description below, in which characters of reference refer to like-named parts in the drawing.

Referring briefly to the drawing, Figure 1 is a front elevational view of the caster as 25 applied to an article of furniture.

Figure 2 is a bottom plan view of the same.

Figure 3 is a vertical sectional elevational view of the caster.

30 Figure 4 is an end elevational view of the caster having a shell type leg body attached thereto.

Figure 5 is a top plan view of the same.

Figure 6 is a perspective view of the roller 35 yoke.

Describing the drawing in detail, the numeral 1 indicates the leg of an article of furniture which has a guard plate 2, of any desired shape, mounted on its lower surface 40 by screws 3. An annular lug 4 surmounting the plate is housed in a corresponding recess in the furniture leg and serves as a centering element. The centre of said guard plate has a threaded hole therein which receives 45 the threaded stud 5 projecting from the upper surface of an annular flange 6. The latter is provided with a pair of diametrically opposed wings 7 and are grasped by the fingers and rotated, when the stud 5 is 50 secured in the threaded hole. The lower surface of said flange 6 has an extending pin

8 which is peened over after being inserted into the hole 9 of the roller yoke 10.

The yoke has two parallel spaced ears 11 between which a roller 12 is rotatably mounted on a pin shaft 13, said shaft being journalled in the holes 14. The roller is preferably of light construction having a central rib 14, a curved spherical traction surface 15, and a hub 16 thru which the pin shaft 13 passes, the latter being peened over after being placed in position between the ears 11.

Various types of guards may be applied to the lower ends of legs, those most frequently used being illustrated in the several views. The guard illustrated in Figure 4 is of the shell type comprising a tapering annular wall 17 which forms a chamber 18, the latter receiving the lower end of the 50 furniture leg. The base 19 of the guard shell has a pair of spaced apart tapering lugs 20 and fit into recesses in the bottom of the furniture leg to prevent the guard shell from being dislocated. The usual threaded hole is 55 provided in the base 19 and receives the stud 5 of the caster flange 6.

It is apparent from the drawing, that the 60 caster herein disclosed is of simple design, efficient as a swivel type, as it is readily rotatable upon member 8, and can be easily replaced by removing the stud 5, the latter operation being accomplished by rotating the wings 7.

We claim:—

A caster comprising a roller, a yoke having a conical hole, ears on said yoke, a pin between said ears supporting said roller, a plate adapted to be secured to an article of furniture and having a threaded hole therein, a flange, a threaded stud on said flange engaging the hole in said plate, a pin rigid on the face of said flange, said pin registering in the conical hole of said yoke, the latter being pivoted on said pin, and wings on 90 the face of said flange adapted to rotate the flange and stud into the threaded hole.

Signed at New York, in the county of New York and State of New York this 30 day of Sept. A. D. 1922.

WILLIAM WINKLER.
ARTHUR H. MILLER.
